CLAIM

The ornamental design for a loudspeaker enclosure, as shown and described.

DESCRIPTION

FIG. 1 is a front, left side, and top perspective view of a loudspeaker enclosure showing the new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in the figures represent unclaimed portions of the loudspeaker enclosure and form no part of the claimed design.
